[57] **CLAIM**

The ornamental design for the combined set of musical instruments and support therefor, as shown and described.

DESCRIPTION

FIG. 1 is a top, front perspective view of a combined set of musical instruments and support therefor showing my new design; and,

FIG. 2 is a bottom view of the xylophone shown in FIG. 1.

The undisclosed portions of the musical instrument set are mirror images of the portions shown.

FIG. 1

FIG. 2
